UNITED STATES PATENT OFFICE.

JOHN EDGAR, OF ROCHESTER, MINNESOTA.

NECK-YOKE.

SPECIFICATION forming part of Letters Patent No. 376,868, dated January 24, 1888.

Application filed March 9, 1887. Serial No. 230,323. (No model.)

To all whom it may concern:

Be it known that I, JOHN EDGAR, of Rochester, in the county of Olmstead and State of Minnesota, have invented certain Improvements in Neck-Yokes, of which the following is a specification.

My invention relates to devices for attaching neck-yokes to the pole and the pole-straps to the neck-yokes; and the object I have in view is to provide means by which these parts may be quickly and readily secured together in such manner that it will be impossible for them to become accidentally detached, while permitting them to be readily detached when desired.

The invention consists, generally, in the construction and combination hereinafter described, and pointed out in the claims.

In the drawings, Figures 1, 2, 3, 4, 5, and 6 are views showing the invention as applied in securing the neck-yoke to a carriage-pole. Figs. 7 and 8 illustrate the invention as applied in securing a pole-strap to a neck-yoke. Fig. 9 is a front elevation of a neck-yoke having my improvement applied thereto.

In all of the figures, 2 represents the portion of the neck-yoke or pole that forms a fixed axle or spindle, and 3 represents the portion of the strap that forms a hub and fits upon said spindle and is adapted to rotate thereon.

5 is a lug or projection extending substantially at right angles to the spindle 2, and in position to engage the strap after it has been placed on the spindle and given a partial rotation thereon.

In Figs. 1, 4, 5, and 6, 2 represents the spindle, which is in this instance a portion of the pole of a carriage, and has a projecting lug, 5, on its lower side.

40 6 represents a portion of the neck-yoke which is provided with a short strap, 3, which has an opening that fits upon the end of the pole. This strap in this instance is the hub that fits upon the spindle and rotates thereon. The neck-yoke is also provided with an auxiliary strap, 4, that is provided with an opening, 3, which is capable of passing over the lug or projection 5 when the neck-yoke is below the pole, as shown in Fig. 4. The neck-yoke strap 3 is placed on the end of the pole, with the neck-yoke below the pole, as shown in Fig. 4,

and is slipped onto the pole until the opening 8 in the strap 4 is carried over the projection 5, when the strap is given a partial rotation upon the spindle, and thereby brought into the 55 position shown in Fig. 1. The projection that is formed by the lower part of the strap 4 encounters the lug 5 and prevents the strap 3 from slipping off the pole. It will then be impossible for the strap to be removed from the 60 pole until its movement has been reversed and the neck-yoke carried below the pole, which of course cannot be done while the device is in use. The strap 4 may be secured to the lower part of the strap 3, as shown in Figs. 5 65 and 6. The operation will be the same as in the other case. The lug on the pole is received into the space between the two straps 3 and 4, and the neck-yoke is thereby locked upon the pole. It is not necessary that the ends of 70 the pole should project as far as usual beyond the neck-yoke, and in many instances I prefer to cut off the pole close to the strap that secures the neck-yoke to the pole, and a shield may be secured to the strap 3 to cover the end 75 of the pole. By dispensing with the projecting end of the pole I obviate the objection arising from the frequent catching of the reins under the end of this pole. This is especially desirable in connection with harvesters or other 80 farm machinery.

The straps 3 and 4 may be metal, if preferred.

In Figs. 7 and 8 the invention is applied to a neck-yoke and strap. The neck-yoke is provided with a spindle, 2, that is secured upon a 85 plate, 13, projecting from beneath the yoke. The end of the yoke forms a projection, 5, beneath which the end of the strap may project. The strap 3, which forms the hub, is placed in the position indicated by dotted lines in Fig. 7, 90 and is placed on the spindle 2. The strap is then turned into the position shown by the full lines in the same figure, carrying its end under the lug 5, by which it is held on the spindle until turned back into the position indicated by dotted lines, when it may be removed.

I claim as my invention—

1. The combination, with the carriage-pole 2, having a projecting lug, 5, thereon, of the 100 neck-yoke having the strap 3, provided with an opening adapted to fit upon the end of the

pole 2, and the auxiliary strap 4, adapted to be carried past the projection and to be engaged with said projection by a partial rotation of the neck-yoke.

5 2. The combination, with the neck-yoke having the strap 3, of the auxiliary locking-strap 4, for the purpose set forth.

3. The neck-yoke having the projecting end, in combination with the plate 13, secured to 10 said yoke and provided with a projecting spin-

dle substantially at right angles to the projecting end of the neck-yoke, substantially as described.

In testimony whereof I have hereunto set my hand this 25th day of February, 1887.

JOHN EDGAR.

In presence of—

ARTHUR L. GOVE,
C. J. PORTER.
